United States Patent Office

Des. 217,968
Patented July 7, 1970

217,968

LAVATORY

William H. Armstrong, Bloomfield Hills, Mich., assignor
to Borg-Warner Corporation, Chicago, Ill., a corpora-
tion of Delaware

Filed Apr. 28, 1969, Ser. No. 16,927

Term of patent 14 years

Int. Cl. D23—02

U.S. Cl. D23—58

FIG.1

FIG.2

FIG.3

FIG.4

FIG.5

FIG. 1 is a top plan view of a lavatory showing my new design;

FIG. 2 is a cross sectional view taken on line 2—2 of FIG. 1;

FIG. 3 is a cross sectional view taken on line 3—3;

FIG. 4 is a fragmentary cross sectional view taken on line 4—4 of FIG. 1; and

FIG. 5 is a fragmentary cross sectional view taken on line 5—5 of FIG. 1.

I claim:

The ornamental design for a lavatory, substantially as shown.
